MECHANICAL FILTER

Reinhard Hellmann, Jackson Heights, N. Y., and Otto Heymann and Franz Tuzek, Berlin-Siemensstadt, Germany, assignors to Siemens & Halske, Aktiengesellschaft, Siemensstadt, near Berlin, Germany, a corporation of Germany

Application June 24, 1938, Serial No. 215,564
In Germany June 25, 1937

6 Claims. (Cl. 178—44)

Coupled mechanical oscillation systems may advantageously be used as electro-mechanical band-pass filters especially inside the tone-frequency or AF range. The closeness or strength of the 5 mechanical coupling, among other factors, is determined by the shape of the attenuation curve. By adopting a loose or slack coupling, it is possible to obtain peaked attenuation curves, in other words, curves possessing a comparatively narrow 10 band-pass width, while the relative band-pass width grows with closeness of the coupling. With mechanical means a plurality of practically useful attenuation networks or four-terminal networks or quadripoles are realizable. A great 15 number of such organizations have been disclosed and suggested.

However, in all of these arrangements the conversion (transduction) of electrical into mechanical energy, and vice versa, is attended with difficulties in the attempt to insure an acceptable 20 efficiency. In electromagnetic and electrodynamic converters there is required a considerable expenditure of material in order to preclude the channel or transmission-range attenuation from assuming 25 very high values. This disadvantage is decisive particularly where low frequencies are dealt with. Where the frequency is high, growth of losses as a general rule affect the transmission range attenuation as well as the slope of the sides 30 of the filter in an unfavorable sense. In other converters or transducers known in the art, for instance, those predicated upon piezo-electric and magnetrostriction phenomena, the attainable efficiency essentially is a function of the electric 35 adaptation or matching. The latter is never even fairly perfect, and it constitutes really the chief problem. Now, all of the drawbacks and difficulties of known arrangements are obviated by the invention.

According to the invention a mechanical filter with an electromechanical converter is so designed that a reinforced conversion of energy is assured. Such energy conversion is obtained by the aid of transducers with an electric or a mechanical 45 source of energy supply, the source of energy to deliver preferably rectified energy.

Amplifying converters or transducers of this kind which comprise an electric energy supply source suited for the purpose are, among others, 50 the pressure or velocity type of transmitters (pickups) known in the prior art, and more particularly also contact-type microphones, carbon-pressure regulators and other real (active) resistances variable by virtue of mechanical shifts 55 or displacements such as liquids with a resistance

being a function of the pressure; moreover, amplifier tubes comprising a mechanically controlled grid are also suited for the above purposes. Particularly suited has proved to be a bolometer arrangement.

Amplifiers which contain a mechanical energy supply source could be realized, for instance, by rotary driven masses whose angular speed is subject to a control action exercised by mechanical means such as friction, eddy-current braking, or the like.

The invention shall be explained in more detail in what follows by reference to the drawing wherein Fig. 1 discloses a diagrammatic perspective view of a mechanical filter according to the invention, Fig. 2 discloses a front view partly in section of a portion of the filter shown in Fig. 1, showing means for providing artificial cooling of the vibratory elements of the filter, Fig. 3 is a modification of Fig. 2, and Figs. 4 and 5 are circuit arrangements of the mechanical filter according to the invention utilizing feed back. In these organizations the mechanical filter is realized and embodied in the form of a tuning fork, while the reinforcing transducer or converter consists of a bolometer organization. It is assumed to be known from the prior art that tuning-fork filters having a frequency-response curve of attenuation are designed in a way resembling that of an electric band-pass filter.

In its fundamental operation the arrangement is illustrated in and will be explained in connection with Fig. 1. A tuning fork 1 is excited in the usual way by the aid of a coil 2 (input of filter). Attached to and supported by the tines 3 thereof are slender wires 4 and 5, and these are included in the two arms of a bolometer bridge arrangement. The latter is so fed across two diagonal points from the source of D. C. voltage supply 6 that the wires, 4, 5, attain a high temperature. If the resistance of these wires undergoes a change, say, as a result of the chilling effect produced incidental to the vibration of the tines 3, an alternating voltage will arise across the bridge resistance 7 (output of filter). Even natural cooling such as set up as a result of the vibratory motion results in such a bridge potential; however, inasmuch as it would lead to frequency doubling, which is undesirable, the regulation of the wire temperature should preferably be insured in an arrangement as illustratively shown in Fig. 2.

In this case a current of air 8 produced, for instance, by a piston or diaphragm type of pump 9 is so passed through slots 10 that the heater

wires 4, 5, are caused to oscillate inside a non-homogeneous velocity field of its marginal zone. In the assumption that the temperature variation of the wires is proportional to the amount of heat carried away by virtue of convection each unit of time, there must be made this additional demand, with a view to insuring the best possible sinuous shape for the output potential, that the drop of speed in the marginal zone should be linear. As a matter of fact, inside a definite range this demand is always fulfilled with adequate approximation. This range governs the greatest amplitude with which the tuning fork may be operated without the output potential evidencing non-linear distortions.

Another exemplified embodiment is outlined in Fig. 3 where the heater wires 4, 5, are immersed in an air current which penetrates the slots 11. These may be covered by vanes 12 whose active edges 13 do not extend parallel to the slots 11, and which are rigidly united with the tines 3 of the fork. In this manner the effective length of the cooling air current is influenced in direct proportion to the deflection of the ends of the tines or prongs so that no special rules or directions need to be followed regarding the speed distribution in the air current at right angles to the axial direction of the wires. This arrangement as well as the one shown in Fig. 2 could, of course, be improved upon by the use of several air ports and heater wires, and these could be connected electrically either in series or in parallel relation.

The distribution of the temperature throughout the cross-sectional area of the heater wires is similar to that of the current distribution in a circular conductor which is located inside an electromagnetic A. C. field. The "depth of penetration" becomes less in both instances as the frequency grows. In the case of the bolometer this leads to a decline in the rate of resistance change, and thus to a diminution (and rotation) of the vector of the output potential, if the amplitude of the tines is assumed to be constant. This is immaterial because in the case of tuning fork filters generally only narrow frequency bands are involved and a constant electro-mechanical transmission ratio is desired. This fact, on the contrary, fixes the frequency limit up to which arrangements of this nature may still be profitably utilized. The same may be extended by using in lieu of the circular heater wires, wires with a cross-sectional form in which the relation between surface area and content or volume is above

such as slender ribbons or tapes, for instance.

An essential improvement, the use of which is not restricted to the present instance, is obtained by feedback relationship between the amplifying converter device and the input of the mechanical filter, said feedback being mechanical, optical or electrical. Thus, for instance, part of the amplified output potential could be re-applied to the input end. This is accomplishable most simply in an organization of the kind shown in Fig. 4. The closeness of the coupling relation is so chosen that the product $|A| \cdot |F|$ stays below unity (where A amplification or gain of the arrangement, and F amount of feedback). In other words, so that no self-oscillation will be able to arise in the system. But the de-attenuating or regenerative effect of the feedback upon the filter characteristic is moreover a function of the phase of the regenerated input potential. Particularly where

high frequencies are dealt with, the phase shift between the vibration of the tines and the output potential may be decisive for the phase balance. For this reason, the insertion of a network 14 in the feedback path may be requisite, the said network having the object to establish and insure such phase relation as may be desired in some special cases. If a maximum amount of regeneration is required for a single frequency, then the input potential and the feedback potential must be in phase. But if, for example, in the case of a band-pass filter the point where an in-phase condition prevails is chosen in the neighborhood of a "corner" (marginal) frequency, the width of the band-pass width may thus be enlarged.

Filters which are furnished with a source of energy resembling the one just described, are dissymmetric four-terminal networks. In the use of such four-terminal networks (or quadripoles) it is often desirable that the attenuation in one direction should be infinitely high. This, indeed, is true of the described organization in the direction from the output to the input ends, provided that no feedback is used. In case of deattenuation or regeneration by means of feedback, return to the input end may be precluded, for instance, by the aid of a differential transformer 15 as shown in Fig. 5. In order that the flux in the transformer 15 due to the feedback current may be zero, a simulation 16 is required. Because of the fact that regeneration is thus made to include both mechanical oscillation systems, the shape of the filter attenuation curve becomes symmetric with relation to the center of the channel or transmission band. In such a scheme the point where an in-phase condition prevails between the input potential and the feedback potential may be connected for both tines or prongs and the same may most suitably be chosen each in the neighborhood of the corner frequency.

If the filter is to be symmetrical, in other words, if the input and the output ends are to be transposable or interchangeable then two like tuning fork sets could be connected together in the manner of a two-wire amplifier or repeater. But the auxiliary means mentioned in the above exemplified embodiment, such as D. C. source of potential supply and diaphragm pump, need not be duplicated.

What we claim is:

1. An electro-mechanical filter comprising input terminals and a coil connected thereto, vibrating means actuated by said input coil, a bolometer bridge arrangement disposed in a heat conducting medium and cooperating with said vibrating means, a source of electrical energy connected to one pair of conjugate bridge terminals, and output terminals connected to the other pair of conjugate bridge terminals.

2. An electro-mechanical filter for low frequencies comprising input terminals and a coil connected thereto, a tuning fork actuated by said input coil, a bolometer bridge arrangement disposed in a heat conducting medium and cooperating with the tines of said tuning fork, a source of electrical energy connected to one pair of conjugate bridge terminals, and output terminals connected to the other pair of conjugate bridge terminals.

3. An electro-mechanical filter for low frequencies comprising input terminals and a coil connected thereto, a tuning fork actuated by said input coil, a bolometer bridge arrangement including a pair of heatable resistance wires which are disposed in a heat conducting medium and which

cooperate with the tines of said tuning fork, a source of electrical energy connected to one pair of conjugate bridge terminals, and output terminals connected to the other pair of conjugate bridge terminals.

5 4. A filter as defined in claim 3, with the characteristic feature that the heat conducting medium consists of a current of air which is passed over the heatable resistance wires in such a way that said wires vibrate in a non-homogeneous 10 velocity field.

10 5. A filter as defined in claim 3, with the characteristic feature that the heatable resistance wires are located inside a current of air constituting the heat conducting medium which is controlled by the filter.

15 6. An electro-mechanical filter comprising input terminals and a coil connected thereto, a tuning fork actuated by said input coil, a heatable filament disposed in a heat conducting medium mounted on each tine of said fork, a pair of resistances electrically connected to said filaments and forming therewith a bridge, a source of electrical energy connected to one pair of conjugate bridge terminals, and output terminals connected to the other pair of conjugate bridge terminals 10
